UNITED STATES PATENT OFFICE.

BEVIS LONGSTRETH, OF KANSAS CITY, MISSOURI.

SALT BOX OR THE LIKE.

Application filed August 21, 1922. Serial No. 583,250.

To all whom it may concern:

Be it known that I, BEVIS LONGSTRETH, a citizen of the United States, residing at Kansas City, in the county of Jackson and State of Missouri, have invented certain new and useful Improvements in a Salt Box or the like, of which the following is a description.

My invention relates to improvements in boxes used for salt or other granular or powdered substances, and more particularly to produce a box of this kind which is simple, compact, convenient, neat and attractive in appearance, reliable, efficient and satisfactory for use wherever found applicable. Another object of my invention is to provide a spout for conveniently pouring the salt or material from the box as needed and movable to inoperative position when the box is not in use, said pouring means or spout being located at a portion of the box that is strongly reinforced, and where substantially all the material in the box may be poured through said spout. Another object of my invention is to provide a sifter means in said box whereby the box may be used as a sifter or shaker whenever desired. Another object of my invention is to so locate the sifter and pouring spout that a label will cover their openings and effectively seal the contents of the box until it reaches the user, who may then remove that portion of the label overlying the sifter or pouring spout opening, or both, when he is ready to use the box. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts;

Figure 1 is a longitudinal sectional view of my invention taken along the line 1—1 of Figure 2;

Figure 2 is a sectional view taken substantially on line 2—2 of Figure 1;

Figure 3 is a fragmentary elevation with parts broken away showing a simple method of attaching the sifter; and

Figure 4 is a fragmentary elevational view with the portions broken away to illus-

trate the manner of attaching the pouring spout.

In the drawings, wherein I have illustrated the preferred embodiment of my invention, there is shown a carton for holding salt or any other desired granular or pulverized product, and consisting of a tubular portion 1 adapted to receive covers 2 and 3 at the opposite ends thereof, said covers having annular flanges 4 thereon to engage and overlie the outer peripheral surface of the ends of the tubular portion 1. In this manner the container is built to a double thickness of material at the ends thereof, which is particularly desirable where the container is constructed of paper board or the like.

At one of the ends of the container, as for instance, the upper end or top, independent openings 5 and 6 are provided through the double thickness of material. A pouring spout 7 is arranged in one of the openings, as for instance, the opening 5, whereby the desired amount of the contents of the box may be quickly discharged or emptied by the user. This pouring spout may be of any suitable or preferred size, shape and material and is preferably channel-shaped, with the web portion 9 extending preferably to the top of the box as shown in Figures 1 and 4, and forming a stop for limiting the inward movement of said spout. There are also shoulders 8 shown formed at the inner ends of the parallel sides of the spout to limit the outward movement of the spout.

In order to more securely hold the spout in place and provide a reinforcement therefor, I have arranged a strip of material 10, preferably fabric, the same secured to both the spout and to the container so as to form a hinge therebetween about which the spout may be swung to its inoperative or operative position.

At the other opening 6 I have arranged a sifter means comprising a dish-shaped member 11, preferably made of screening or any other suitably perforated material and having a flange 12 to overlie the peripheral surface of the container. A sheet of fabric 13 may be secured to this flange 12 and to the adjacent portion of the outer surface of the container so as to securely hold said sifter in place and provide a reinforcement therefor. The screen may be frictionally inserted in place if desired and may be

bulged so that the diameter at the inner end is larger than at a point outwardly thereof. It will be noted that both the sifter and spout are secured in place at substantially 5 the corner of the box, so that all of the material therein may be emptied.

By providing a screening or sifting member of dish-shaped construction a larger screening area is afforded which permits the 10 egress of the salt from all directions, or in other words from the sides as well as the surface of the screen paralleling the box wall.

It should be observed that the sifter or 15 screening member is positioned in the side of the box adjacent one end; and there is a distinct advantage in positioning the screen in the side rather than on the top. In use, the box is tilted at an angle of about 45° in 20 order to permit the sifting of the salt, whereas when the screen is on the top the container must be turned upside down and shaken. When the container is inverted the entire body of the salt within the container 25 pressing against the screen tends to cake and prevent the easy and free screening or sifting of the salt which is obtained when the screen is in the side of the container. Another advantage is that with the screen in 30 the side of the container the salt does not tend to stick in the screen and to fill up the perforations. With a screen on the top of a container, when the same is inverted to sift the salt, the salt drops into the screen and 35 particles remain fast, even after the can has been returned to an upright position.

In order to effectively seal the spout and sifter during shipment and to make a neater looking package, I have arranged the usual 40 label 14 to cover both the sifter and spout, sealing them, so that when the package reaches the consumer it is necessary only that he remove that portion of the label covering said parts in order to make use of the 45 box in the preferred manner. The box may be used for salt, sugar, flour, or the like, or for scouring powders, etc., the particular use being immaterial.

It will be noted that the openings are positioned so that when the box is tilted for 50 discharge of the contained material through one of the openings, the same will not gravitate toward the other opening. Although both the spout and the sifter are covered by 55 a frangible seal, it is customary for the seal to be broken shortly after purchase of the package, and if the sifter and pouring spout openings were positioned adjacent one another when the box is tilted to discharge material through the pouring spout it would 60 freely discharge through the sifter screen. The same would be true were the sifter provided with a closure and the pouring spout adapted to freely discharge material upon 65 mere tilting of the container without man-

ual operation thereof. Obviously, it is merely necessary to dispose the openings so that when the box is tilted both openings are not, at the same time, in the lines of the gravitational flow of the material, and ordinarily this would be when the openings are substantially on opposite sides of the longitudinal center of the box; the spacing of the openings approximately 90° around the wall of the container will generally accomplish 70 the same result, it not being necessary to position them diametrically opposite, as shown in the drawings.

Having thus described my invention, it is 80 obvious that various immaterial modifications may be made in the same without departing from the spirit of my invention; hence I do not wish to be understood as limiting myself to the exact form, construction, arrangement and combination of parts here- 85 shown and described, or uses mentioned.

What I claim as new and desire to secure by Letters Patent is:

1. A box for packaging salt and the like, comprising a holding chamber having a 90 sifter opening, a sifter member in said opening, said member being adapted to discharge material upon mere tilting and shaking of the box without manual operation of a closure therefor, said chamber having also a pouring spout opening independent of said sifter opening, and positioned substantially on the opposite side of the longitudinal center of the container from said sifter opening, whereby when material is discharged through one of said openings it will not tend to gravitate toward the other opening, and a pouring spout in said last mentioned opening.

2. A box for packaging salt and the like, comprising a holding chamber having a 100 sifter opening positioned in the side thereof, a sifter device in said opening, said chamber having also a pouring spout opening independent of said sifter opening, and placed a substantial distance therefrom transversely of said container, whereby when the contained material is discharged through said spout opening it will not tend to gravitate 110 toward the sifter opening, and a pouring spout device in said spout opening, at least one of said devices being adapted to discharge material upon mere tilting and shaking of the box without manual operation of a closure therefor.

3. A box for packaging salt and the like, comprising a chamber having a sifter opening positioned in the side thereof, a normally open sifter device in said opening, said chamber having also a pouring spout opening independent of said sifter opening, and positioned in the side of the container substantially on the opposite side of the longitudinal center of the container, whereby when the container is tilted to discharge the ma- 120 125 130

material from one of said openings the material will not tend to gravitate toward the other opening, and a pouring spout device positioned in said spout opening, at least one of said devices being adapted to discharge material upon mere tilting and shaking of the box without manual operation of a closure therefor.

4. A box for packaging salt and the like, comprising a holding chamber having a discharge opening and a pouring device therefor, said chamber having, also, a second discharge opening independent of said first opening and positioned substantially on the 15 opposite side of the longitudinal center of the container from said first discharge opening, whereby when the contained material is discharged through one of said openings it will not tend to gravitate toward the other opening, a sifter device in the second discharge opening, at least one of said devices being adapted to discharge the material upon mere tilting and shaking of the box without manual operation of a closure therefor.

5. A box for packaging salt and the like, comprising a container made of a tubular body portion and end covers, one of said end covers having a flange overlying the tu-

bular portion and sealed thereto to provide 30 a double thickness for the side walls adjacent one of the ends of the container, said container having an opening through said double thickness of material, and a sifter screen comprising a dish-shaped portion inserted through said opening at the double thickness of material and having a flange 35 overlying the wall of the container around said opening.

6. A box for packaging salt, comprising a 40 container made of a tubular portion and end covers having flanges overlying said tubular portion and sealed thereto to provide a double thickness at the ends, an opening through said double thickness of material, a 45 sifter screen comprising a dish-shaped part insertable through said opening at the double thickness of material, and having a flange overlying the wall of said container, and fabric means engageable with said 50 flange for securing said screen in place.

In testimony whereof, I have hereunto signed my name in the presence of two subscribing witnesses.

BEVIS LONGSTRETH.
